UNITED STATES PATENT OFFICE

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS

LOCOMOTIVE OR TRUCK

Application filed March 21, 1928. Serial No. 263,245.

This invention relates to improvements in locomotives or trucks and has as its object to provide an improved construction affording relative flexibility of the supporting wheels 5 and axles so as to readily follow uneven track.

A usual type of construction of locomotives comprises a plurality of axles with supporting wheels thereon. Said axles are journaled in suitable axle boxes carried by the locomotive frame and have springs interposed between each axle box and the frame. Such a construction allows the ends of an axle to move vertically a limited distance, depending upon the resiliency of the springs, thereby 15 affording limited flexibility of movement of opposite ends of the axle.

In my present invention, I provide an equalizing device in which the opposite ends of an axle have a bell crank lever interposed 20 between them and the frame and are connected together by a transversely extending member pivotally connected to a transverse floor member of the frame so as to allow the axle to swing in a vertical plane independent 25 of the resiliency of the springs.

My invention may be more clearly understood by referring to the drawings wherein:

Figure 1 is a fragmentary top plan view of one type of locomotive having my invention 30 embodied therein;

Figure 2 is a fragmentary sectional view of one type of locomotive with parts of the motor shell and wheel broken away to more clearly show my invention;

Figure 3 is a fragmentary front end view 35 of a locomotive with parts broken away and in section to show the details of my invention;

Figure 4 is a fragmentary view showing 40 the connection of one arm of one of the bell crank levers to a transverse bar connecting the two bell crank levers together; and

Figure 5 is a perspective view of a spring saddle used in my invention.

In the drawings, one embodiment of my 45 invention is illustrated as applied to a locomotive frame having side plates 2, 2, an axle 3 and supporting wheels 4, 4. Suitable journal boxes 5, 5, are mounted adjacent opposite 50 ends of the axle and are movable vertically

between oppositely disposed guide plates of a pedestal 7, 7, which may be of any suitable construction.

The locomotive frame is supported on the journal boxes 5, 5, through the medium of 55 an equalizing device constructed as follows:

A pair of bell crank levers 9, 9, are pivotally mounted on opposite sides of the locomotive frame above their respective axle boxes to swing in a vertical plane longitudinally of the locomotive. The bell crank levers are pivotally mounted on the locomotive frame by means of two bearing pins 10, 10, supported in brackets 11, 11, carried on the side plates 60 2, 2, of said locomotive frame. One arm 12 of the bell crank lever 9 extends from its axis rearwardly to a saddle 14. Springs 15 15 which may be of the usual helical type or their equivalent are interposed between each of the journal boxes 5, 5, and the spring saddles 65 14, 14. In Figures 2 and 5 it may be seen that the saddle 14 has a pair of ribs 14^a projecting upwardly therefrom which have a curved recess therein to receive a heel 12^a of the lever arm 12 of the bell crank lever 9. Another arm 16 of the bell crank lever 9 extends 70 downwardly from its pivotal axis to a transverse pivotally movable bar 18 for connecting the two bell crank levers together.

Figure 4 shows a detail of the connection of 75 the arm 16 to the transverse bar 18. It may be seen that the lower portion of the arm 16 projects through an aperture 18^a in the bar 18 and that the lower portion of said arm is 80 recessed to fit around the bar 18 and that said recess has a curved face to provide a bearing surface for the arm 16 on the transverse bar 18. Clearance is allowed in the recessed portion of the arm 16 to allow for 85 the arcuate movement of said arm. The transverse bar 18 is pivotally mounted at its central portion to pivot on a vertical axis on a floor or bottom plate 20 which joins the side plates 2, 2, of the locomotive frame. A pin 22 journaled in the bottom plate 20 at 90 one end, and in a bracket 23 at its opposite end, pivotally connects the transverse bar 18 to the bottom plate 20. In Figures 2 and 3 it 95 may be seen that the central portion of the pin 22 is squared to fit in a corresponding 100

squared aperture in the transverse bar 18. The arrangement is such that vertical movement of one axle box will cause movement of one bell crank lever which will move the transverse bar 18 about its pivotal axis and therefore move the opposite bell crank lever in the opposite direction which will in turn move the axle box connected to said bell crank lever in an opposite direction to that of the first named axle box.

In applying my invention to a locomotive of the two axle type, it is preferable to mount one of the axles in the usual manner, that is to say, without any equalizing device to afford the desired stability to the frame, while the other supporting axle is mounted as above described so as to afford a wide range of flexibility with respect to the frame and the one stabilizing axle connected therewith. By means of this arrangement the load is maintained evenly on all of the supporting wheels while moving over uneven track.

Although I have shown and described one form in which my invention may be embodied, it will be understood that the construction and the arrangement of the various parts may be altered without departing from the spirit and scope thereof. Furthermore, I do not wish to be construed as limiting myself to the specific embodiment illustrated in the drawings, excepting as it may be limited by the appended claims.

I claim as my invention:

1. In a car, a frame, an axle having supporting wheels, and an equalizing device comprising a pair of rocking members, each pivotally mounted on opposite sides of the frame and affording a vertically movable support for one end of said axle, and a rocking member movable in a horizontal plane connecting said first mentioned rocking members together.

2. In a car, a frame, an axle having supporting wheels, an equalizing device comprising a pair of bell crank levers, each pivotally mounted on transversely extending axes at opposite sides of the frame and affording a vertically movable support for one end of said axle, and a rocking member movable about an axis perpendicular to the axes of said bell crank levers and connecting said bell crank levers together.

3. In a car, a frame, an axle movable in a substantially vertical plane with respect to said frame, supporting wheels for said axle, and an equalizing device comprising a pair of longitudinally disposed bell crank levers pivotally mounted on opposite sides of the frame and affording a vertically movable support for one end of said axle, and a rocking member movable about an axis perpendicular to the axes of said bell crank levers connecting said bell crank levers together.

4. In a car, a frame, an axle movable in a

substantially vertical plane with respect to said frame, supporting wheels for said axle, and an equalizing device comprising a pair of longitudinally disposed bell crank levers pivotally mounted on opposite sides of the frame and affording a vertically movable support for one end of said axle, and a member extending transversely of the car frame connecting said bell crank levers together, said member being movable about a vertical axis at its central portion and being below the axis of said axle.

5. In a car, a frame, an axle having supporting wheels, a floor plate for said frame connecting the sides of said frame together, and an equalizing device comprising a pair of rocking members, each pivotally mounted on opposite sides of the frame and affording a vertically movable support for one end of said axle, and a rocking member pivotally mounted on said floor plate and connecting said first mentioned rocking members together.

Signed at Chicago, in the county of Cook and State of Illinois, this 19th day of March, 1928.

WILLIAM W. SLOANE.
